UNITED STATES PATENT OFFICE.

CHARLES M. BREHM, OF DAYTON, OHIO.

DIE.

1,304,151.

Specification of Letters Patent.

Patented May 20, 1919.

Application filed February 8, 1919. Serial No. 275,731.

To all whom it may concern:

Be it known that I, CHARLES M. BREHM, a citizen of the United States, residing at Dayton, in the county of Montgomery and State 5 of Ohio, have invented certain new and useful Improvements in Dies, of which the following is a specification, reference being had therein to the accompanying drawing.

This invention relates to dies, particularly 10 to trimming dies and has for its object to provide a trimming die which will operate in one or more lateral directions whereby the trimming operations will be completed on one stroke of the press in which the die 15 is used.

My improved die is especially adapted to trimming hollow articles, either round, rectangular, or irregular shaped, and will trim the edge of such articles complete on one 20 stroke of the press.

As here shown, the particular die embodying the invention is designed to trim the edge of a round, cup-shaped punching, the edge being trimmed uniformly. It will be 25 obvious, however, from the detail description of the invention that articles of a wide variety in shapes, having uniform or irregular edges, may be treated in suitable dies constructed on the principles of my invention.

The main object to be attained in the improved dies is cheapness in production. As far as I am aware, and speaking from years 35 of experience in modern methods in shop practises, no method or principle in die construction has been heretofore developed whereby operations of the character contemplated in my invention are possible. Under present practises such operations are usually 40 performed on a mill or lathe which is much slower and therefore increases cost of production.

The particular die here shown is a single 45 unit die, but it will be understood that the invention is readily adaptable to multiple unit dies, and that the rate of production may therefore be greatly increased over the normally rapid production of a single unit die.

Also, as here shown, the product is inserted into and removed from the die by hand, but it is obvious that dies embodying 50 the invention are readily adaptable to automatic means for introducing and removing the product. Such means do not constitute

any part of the present invention and are therefore not shown.

While my improved die embodies an important principle and function not heretofore employed in die construction I have been 60 able to apply in the application of the invention the well known rules governing die construction, such as strength and stress of metals, provision for grinding, clearance, etc., so that the construction is substantial 65 and the die in all respects is effective for the purposes of the invention.

Referring to the drawings:

Figure 1 is a vertical cross sectional view of the male and female die members and 70 showing the manner of securing the die to an ordinary press;

Fig. 2 is a perspective view of the male member of the die;

Fig. 3 is a perspective view of the die base 75 and female member of the die showing the latter in its normally raised position above the face of the die base the same as in Fig. 1.

Fig. 4 illustrates the unfinished and finished product, respectively, to be adapted to the particular die here shown and consisting of a cup-shaped punching having an edge requiring finish to predetermined dimensions;

Fig. 5 is a perspective view of the die 85 base.

Fig. 6 is a cross sectional view of the die base taken on the line 6—6 of Fig. 5, showing two of the same projections on the inner 90 faces of the die base;

Fig. 7 is a plan view of the movable die member showing the cam projections on the edges thereof whereby in coöperation with the cams in the die base lateral movement is 95 imparted to the female die member;

Figs. 8 and 9 are perspective views of the female die members each showing two edge faces of the die member and the arrangement of the cam projections thereon;

Figs. 10, 11 and 12 are detail sectional views showing the cam formation on each of the three edge faces of the die member, as shown in Figs. 8 and 9.

As here shown the invention consists of a 105 die supporting base 1 and the die block 2, the latter being secured to the base block in any suitable manner, as by screws 3, and having a triangular-shaped aperture 4 extending through the central portion thereof 110

in which the die member 5 is operatively supported having limited lateral and vertical movement therein.

The member 5 is supported by posts 6, one 5 at each corner thereof, the upper ends of the posts being retained in yieldable relation thereto by short pins or studs 7 secured in the block and cooperating with holes 8 in the end of the post.

10 The posts 6 extend through apertures 9 in the base, 1, their opposite ends resting in shallow seats in a plate 10 disposed in a horizontal plane below the base 1.

15 The plate 10 is supported on and is normally pressed upwardly by springs 11 which telescope guide rods 12 extending through apertures 13 in the plate 10 and having their upper ends threaded into the base 1; the lower ends of the rods being threaded and 20 provided with nuts and supporting washers, whereby the tension of the springs may be adjusted.

25 Adjacent their upper edges each of the walls of the aperture 4, as here shown, is provided with an inwardly projecting rib or flange 14 substantially triangular shaped in cross section, the upper and lower faces of which function as cams in co-operation with cam surfaces 15—16—17 formed respectively in the edge faces of the die member 5.

30 It will be observed that the cam elements in the aperture 4 are arranged in the same horizontal plane and that they are in all respects equal or uniform, terminating in clearance spaces 18 provided at the corners of the aperture. However, the cam surfaces 15—16—17 are arranged in different horizontal planes.

35 It is in the construction and arrangement of these cam elements and the movements transmitted thereby to the die member 5 that the main object of the invention is realized. It will be apparent that with the member 5 in normal position in the aperture 4, i. e., its upper surface projecting above the upper surface of the die block 2 as shown in Figs. 1 and 3 of the drawings, and the lower cam surface 15 cooperating 40 with one of the cam projections 14, if pressure is applied to the die member it will be moved vertically and also laterally first in a direction at right angles to the longitudinal axis of the cam 15 and then as the downward movement continues and the cam surface 15 passes out of contact with the co-operating cam 14, the cam surface 16 is brought into engagement with the second of the cams 14, the die block is moved laterally in a plane at an angle of 120° to its first plane of movement, and finally, as the cam surface 17 contacts with the third cam 14, the die member is moved laterally, in a plane at an angle of 120° to the second plane 55 of movement.

The upper face of the die block 5 has a central aperture 20, the bottom of which is formed by a plug 21 which is normally held in raised position by a spring 22 which is supported on a threaded plug 19; the lower portion of the aperture being larger in diameter than the upper portion a shoulder 23 is formed with which a corresponding shoulder 24 of the plug 21 contacts and defines, therefore, the upper limit of movement of 75 the plug 21.

The opposite or punch member of the die consists of the usual base plate 25 and stem 26; the base plate having secured to the under side thereof, by the usual screw and 80 dowel mounting, a triangular shaped block 27 which conforms in its surface dimensions substantially to the dimensions of the aperture 4.

85 For the immediate application of the invention the exposed face of the punch block 27 is provided with a depression or clearance space 28 at the center of which the punch, or rather as here used, the trimming member 29 is secured to the block, and secured in the member 29 and projecting upwardly therefrom is the seating pilot 30; the end surface of the trimmer 29 being slightly less than flush with the outer face of the block 27.

90 From the foregoing detail description the construction and operation of my improved die will be understood. The operation may be briefly summarized as follows:

95 The unfinished product in the present instance consists of a round, cup-shaped 100 punching, having an irregular edge, as shown in Fig. 4, requiring trimming.

105 The unfinished articles are placed in the aperture 20 by hand and, as here shown, are also removed by hand after the trimming operation.

110 Upon the stroke of the press the punch member is projected downwardly until the trimming member 29 enters the upper portion of the article in the die; the seating pilot 30 contacting with the bottom of the article forces it down in the aperture 20 to the required depth; then as the down stroke of the press is continued, the die member 5 is forced downwardly by contact therewith 115 of the punch member 27, and is actuated laterally three ways in rapid succession by functioning of the cams 14 and 15—16—17; thus causing the trimmer 27 to cut away the entire portion of the irregular projecting 120 edge of the article and reducing it to the regular finished edge.

125 It will be understood that the springs 11 relative to the die member 5, and the spring 22 relative to the seating plug 21 act, respectively, to cause these parts to yield sufficiently to compensate for slight variations in adjustment of the upper and lower die members and that accuracy of production may thus be maintained within required 130

limits, and that excessive pressure between the parts and breakage thereof will not occur.

Having thus fully described my invention, 5 what I claim as new and desire to secure by Letters Patent, is:

1. In a die, the combination, a stationary member having an aperture therein, a member operable in said aperture, cam elements 10 arranged respectively in said aperture and on said movable member; and a member movable relative to said members and adapted to move the second member vertically, whereby the cam elements will act to move 15 said second member successively laterally in a plurality of planes.

2. In a die, the combination, a stationary member having an aperture therein, a member operable in said aperture, cam elements 20 arranged respectively in said aperture and on said movable member; and a member movable relative to said members and adapted to move the second member vertically, whereby the cam elements will act to move 25 said second member laterally.

3. In a die, the combination, a stationary member having an angular shaped aperture therein, a corresponding angular shaped member operable in said aperture, cam elements 30 arranged respectively in said aperture and on said movable member; and a member movable relative to said members and adapted to move the second member vertically, whereby the cam elements will 35 act to move said second member successively laterally in a plurality of planes.

4. In a die, the combination, a stationary member having a triangular shaped aperture therein, a triangular shaped member operable in said aperture, cam elements 40 arranged respectively in said aperture and on said movable member; and a member movable relative to said members and adapted to move the second member vertically, 45 whereby the cam elements will act to move said second member successively laterally in a plurality of planes.

5. In a die, the combination, a stationary member having an aperture therein, a member operable in said aperture and having 50 means to seat an article therein, cam elements arranged respectively in said aperture and on said movable member, a member movable relative to said members, adapted to move 55 the second member vertically, and having a projection adapted to engage said article, whereby the cam elements will act to move said second member successively laterally in a plurality of planes, thereby causing a portion 60 of said article to be removed.

6. In a die, the combination, a stationary member having an aperture therein, a member operable in said aperture and having 65 means to seat a hollow article therein, cam elements arranged respectively in said aper-

ture and on said movable member, and a member movable relative to said members, adapted to move the second member vertically, and having a projection adapted to engage the hollow portion of said article, 70 whereby the cam elements will act to move said second member successively laterally in a plurality of planes, thereby causing the edge of said article to be removed.

7. In a die, the combination, a stationary 75 member having an aperture therein, a member operable in said aperture and having means to seat a hollow article therein, cam elements arranged respectively in said aperture and on said movable member, a member 80 movable relative to said members, adapted to move the second member vertically, and having a projection adapted to engage the hollow portion of said article and a second projection adapted to seat the 85 article in said aperture, whereby the cam elements will act to move said second member successively laterally in a plurality of planes, thereby causing the edge of said article to be removed. 90

8. In a die, the combination, a stationary member having an aperture therein, a member operable in said aperture and having means to seat a hollow article therein, cam elements arranged respectively in said aperture and on said movable member, and a member movable relative to said members, 95 adapted to move the second member vertically, and having a projection adapted to engage the hollow portion of said article, 100 whereby the cam elements will act to move said second member successively in a plurality of planes, thereby causing the edge portion of said article to be removed to a predetermined extent. 105

9. In a die, the combination, a stationary member having an aperture therein, a member operable in said aperture and having means to seat a hollow article therein, cam elements arranged respectively in said aperture and on said movable member, and a member movable relative to said members, adapted to move the second member vertically and having a part adapted to enter the hollow portion of said article to a predetermined extent, whereby the cam elements will act to move said second member successively in a plurality of planes laterally, thereby causing the edge portion of said article to be removed to an extent determined by the extent of projection of said part in said article. 115

10. In a die, the combination, a stationary member having an aperture therein, a member operable in said aperture and having 125 means to seat a hollow article therein, cam elements arranged respectively in said aperture and on said movable member, a member movable relative to said members, adapted to move the second member vertically 130

and having a part adapted to enter the hollow portion of said article and a clearance space surrounding said part for the projecting edges of the article, whereby the 5 cam elements will act to move said second member successively laterally in a plurality of planes, thereby causing the edge of said article to be removed.

11. In a die, the combination, a stationary 10 member having an aperture therein, a member operable in said aperture and having a flat face with an aperture for seating a hollow article therein, cam elements arranged respectively in said aperture and on said 15 movable member, a member movable relative to said members having a flat face with a depression therein, a part extending vertically in said depression and having its end substantially flush with said face and 20 adapted to project into the hollow portion of said article; the face of said last member being adapted to engage the face of the second member and move the same vertically, whereby the cam elements will act to move 25 said second member successively laterally in a plurality of planes, thereby causing the edge of said article to be removed.

12. In a die, the combination, a base plate having a stationary die member secured 30 thereto, said member having an aperture therein, an operable member yieldably supported in said aperture from the base plate, cam elements arranged respectively in said aperture and on said movable member; and 35 a member movable relative to said members and adapted to move the second member vertically, whereby the cam elements will act to move said second member successively laterally in a plurality of planes.

13. In a die, the combination, a base plate having a stationary die member secured thereto, said member having an aperture therein, an operable member supported in 40 said aperture on posts seated on a plate resting on springs suspended on rods secured to the base plate, cam elements arranged respectively in said aperture and on said movable member, and a member movable relative to said members and adapted to move 45 said second member vertically, whereby the cam elements will act to move said second member successively laterally in a plurality of planes.

14. In a die, the combination, a base plate 50 having a stationary die member secured thereto, said member having an aperture therein, an operable member supported on springs suspended from the base plate, cam elements arranged respectively in said aperture and on said movable member; and a member movable relative to said members

and adapted to move the second member vertically, whereby the cam elements will act to move said second member successively laterally in a plurality of planes. 55

15. In a die, the combination, a base plate having a stationary die member secured thereto, said member having an aperture therein, an operable member supported on springs suspended from the base plate, cam 70 elements arranged respectively in said aperture and on said movable member, whereby when said operable member is depressed the cam elements will act to move said member laterally in a plurality of planes. 75

16. In a die, the combination, a stationary member having an aperture therein, a member operable in said aperture, cam elements arranged respectively in said aperture and on said movable member, whereby when said 80 operable member is depressed the cam elements will act to move said member laterally in a plurality of planes.

17. In a die, the combination, a stationary member having an aperture therein, a member operable in said aperture, cam elements arranged in the same plane in said aperture and cam elements arranged in different planes on the operable member, whereby when the operable member is depressed the 90 cam elements will act successively to move said member laterally in different planes. 95

18. In a die, the combination, a stationary member having an aperture therein, a member operable in said aperture and normally 100 extending above the face of the first member, cam elements arranged respectively in said aperture and on said movable member; whereby the cam elements will act to move said second member successively in a plurality of planes, and means to restore the operable member to normal position. 105

19. In a die, the combination, a stationary member having an aperture therein, a member operable in said aperture and normally 110 extending above the face of the first member, cam elements arranged respectively in said aperture and on said movable member; whereby the cam elements will act to move said second member successively, and means to restore the operable member to normal position. 115

20. In a die, the combination, a stationary member having means to support an article thereon, a member moving laterally relative 120 to the stationary member, and a member movable relative to the laterally movable member, whereby a portion of said article will be removed.

In testimony whereof, I affix my signature. 125

CHARLES M. BREHM.
